of Delaware

Application June 28, 1946, Serial No. 679,988

6 Claims. (Cl. 250—27)

1

My present invention generally relates to electronic timer circuits, and more particularly to thyratron timer circuits.

A reliable electronic timer circuit should possess these following characteristics: it must have good reset accuracy; it must be stable and flexible as possible; and it should be relatively inexpensive to construct. It is, accordingly, an important object of my present invention to provide a timer circuit which possesses many advantages over prior timer circuits, and which is characterized by the inclusion of a grid-controlled, gas-filled electron discharge tube as a relay device.

Another important object of my invention is to provide a thyratron timer circuit which, with relatively simple modifications, may function as a time delay relay or a time interval relay.

A further object of my invention is to provide an electronic timer circuit which comprises essentially a positive and negative rectifier and a thyratron relay.

Another object of my invention is to provide a thyratron timer circuit adapted for a wide variety of uses such as timing the exposure of photographic paper during printing or enlargement, control of time current is applied to welding electrodes and tube high current emission testing.

Still other objects of my invention are to improve generally the efficiency and reliability of electronic timers, and more particularly to provide relatively inexpensive thyratron timing circuits which dispense with power transformers, and which utilize standard 60 cycle alternating current power relays in the thyratron plate circuit.

Still other features and objects of my invention will best be understood by reference to the following description, taken in connection with the drawings, in which I have indicated diagrammatically several circuit organizations whereby my invention may be carried into effect.

In the drawings:

Fig. 1a shows a circuit diagram of a timer circuit embodying my invention;

Fig. 1b is a circuit diagram of a modification;

Fig. 2 is a schematic diagram of an illustrative use of the timer circuit;

Fig. 3 graphically shows the timing condenser charging characteristics of the timer circuits of Figs. 1a and 1b;

Fig. 4 is a modification to provide a time delay relay; and

Fig. 5 shows an additional modification where-

2

in the circuit functions as a time interval relay.

Referring now to the accompanying drawings, where like reference numerals in the different figures denote similar circuit elements, I have shown in Fig. 1 an electronic timer circuit which possesses various advantages. Essentially the timer circuit comprises a positive rectifier and a negative rectifier for the input current. That is, opposed rectifiers provide rectified voltages of opposite polarity. The source of input current is assumed to be connected to the leads 1, 1', and a 60 cycle alternating current source may be employed. The source voltage may be chosen from 115 to 230 volts. The output leads 2, 2' deliver the 60 cycle alternating current voltage to any desired utilization device which is to be energized at predetermined time intervals. In addition to a pair of opposed rectifiers, the circuit includes a grid-controlled gas tube. The latter may be a thyratron of any well known and suitable type.

Referring more specifically to Fig. 1, the numeral 3 denotes a double diode tube which may be of the 6H6 or 6AL5 types. This tube provides a pair of diodes for the opposed rectifier circuits. Thus the diode D₁ has its anode 4 connected to lead 5, which, in turn, is connected to the input current lead 1. The cathode 6 is connected through resistors 7 and 8 to a lead 9, which is connected to the adjustable element 10 of a push switch. The contact 11 of the push, or closing, switch is connected to the input current lead 1'.

The junction of resistors 7 and 8 is indicated as having a potential of positive polarity relative to the low potential lead 9, and it will be noted that resistor 8 is shunted by bypass condenser 12. The second diode D₂ has its cathode 13 connected to lead 5, while its anode 14 is connected to lead 9 through the series connected resistors 15 and 16. The resistor 16 is shunted by bypass condenser 17, and the junction of resistors 15 and 16 is indicated as having a potential of negative polarity relative to the low potential lead 9. It will, therefore, be observed that the junctions 18 and 19 are at potentials of opposite polarity due to the fact that the respective rectifiers D₁ and D₂ are oppositely poled.

The thyratron relay tube 20 may be of the 2050 or 2D21 types. The black dot within the tube envelope indicates that the tube is gas-filled. The cathode 21 of tube 20 is connected by lead 22 to the push switch arm 10. The plate 23 of the thyratron tube is connected through the winding 24 of the electromagnetic relay to the lead 5. It will be noted that winding 24 is

shunted by resistor 25 connected in series with condenser 26. The control grid 27 of the thyratron tube 20 is connected through the series resistors 28 and 29 to the junction point 19. The shield grid 30 of the thyratron tube is connected to the cathode lead 22, which, in turn, is connected to the low potential output lead 2'.

The cathode resistor 8 is provided with a slider 31, and the latter is connected by lead 32 to the adjustable arm 33 of a range switch. The latter functions to connect a desired one of three condensers 34, 35 or 36 from the junction point 37 between resistors 28 and 29 to lead 32. The electromagnetic relay is of the double pole-double throw type. The double pole-double throw switch is schematically represented, since those skilled in the electrical art are fully acquainted with the manner of constructing such a switch device which is adapted to be actuated in accordance with the energization of the relay winding 24. The double pole-double throw switch includes four contacts 38, 39, 40 and 41. The contact 40 is open or free, while contact 41 is connected by lead 42 to the junction point 37. The contact 38 is connected by lead 43 to the lead 5, and the contact 39 is connected by lead 44 to the current input lead 1'.

The junction of the pair of switch arms 45, 45' is connected by lead 46 to current output lead 2, and the junction of the pair of switch arms 47 and 47' is connected by lead 48 to the current output lead 2'. It will, therefore, be seen that the pair of contacts 38 and 39 has associated with it the corresponding pair of switch arms 45 and 47, while the pair of contacts 40 and 41 has associated with it the respective switch arms 45' and 47'. The mechanical structure of the switch is such that the switch arms 45 and 45' are arranged in the manner of a "seesaw," as is, also, the case of the switch arms 47 and 47'. Of course, any suitable biasing device, such as a coil spring, may be used to maintain the switch arms 45' and 47' in electrical contact with contacts 40 and 41 respectively in the absence of current flow through the winding 24. Upon current flowing through winding 24, however, the switch arms 45 and 47 will be pulled into contact with contact points 38 and 39 respectively, thereby opening the corresponding switches 40, 45' and 41, 47'.

The electronic timer circuit works through one cycle of operation in the following manner. Momentarily closing push switch 10, 11 closes the electrical circuits through diodes D₁, D₂ and thyratron 20. This is readily seen by tracing the circuit from lead 1 to lead 5, through diode D₁, resistors 7 and 8, lead 9, switch 10, 11 and input lead 1'. A similar path can be traced through diode D₂, except that the current now flows from lead 9, resistors 16 and 15 and diode D₂ to lead 5. In the case of tube 20 the circuit is traced as follows: lead 1, lead 5, coil 24, plate 23, cathode 21, lead 22, switch 10, 11 and lead 1'. Voltage is applied to the respective diodes D₁ and D₂ and to thyratron 20. As a result points 18 and 19 assume the noted respective positive and negative potentials due to the charging up of condensers 12 and 17. Concurrently, the thyratron 20 draws current thereby energizing coil 24 whereby switches 45, 38 and 39, 47 are closed and switches 40, 45' and 41, 47' are opened.

Closure of switches 38, 45 and 39, 47 effect respectively two actions. Switch 38, 45 provides a path from lead 1 to output lead 2, while switch 39, 47 provides a path from lead 1' to output lead

2'. Thus, even though push switch 10, 11 is only momentarily closed, the switch 39, 47 closes a shunt path across open switch 10, 11. The completed circuit, then, may be traced as follows: input lead 1, lead 5, lead 43, switch 38—45, lead 46, output lead 2, output lead 2', lead 48, switch 39—47, lead 44 to input lead 1'. Assuming that switch arm 33 has been adjusted to select timing condenser 34, as shown, as soon as condensers 12 and 17 are charged (this happens almost immediately upon closure of push switch 10, 11) condenser 34 starts to charge.

The charging of condenser 34 proceeds, since the leakage, or discharge, circuit is open. The discharge circuit is traced as follows: point 37, lead 42, switch 41, 47', lead 48 to lead 22. The charging current flowing through resistor 29 applies a positive voltage to the thyratron grid 27, since the grid is connected through resistor 28 to the junction of resistor 29 and timing condenser 34. The thyratron cathode 21 is connected to the junction of the condensers 12 and 17. In other words, and assuming slider 31 is set at the positive or upper end of condenser 12, the input terminal of condenser 34 is connected to the positive terminal of a source of voltage (charged condenser 12) while the left end of resistor 29 is connected to the negative terminal of a second source of voltage (charged condenser 17).

Hence, adjustment of slider 31 on resistor 8 determines the period or interval during which grid 21 will be above its critical potential to permit "firing" of the thyratron. The size of the condenser 34, 35 or 36 chosen by switch arm 33, of course, dictates the period of time it will take to charge the timing condenser. The slider 31 is, therefore, a fine time interval adjustment, while switch arm 33 is a coarse time interval selector switch. Eventually the grid voltage will go from a positive voltage to a negative voltage, and finally pass the point of critical grid voltage. At this point the thyratron becomes non-conductive thereby de-energizing relay coil 24. Switches 38, 45 and 39, 47 open, while switch 41, 47' closes. The circuit to output leads 2, 2' is broken, while the discharge circuit for condenser 34 is closed. The discharge of condenser 34 clears the system for the next cycle in response to closing push switch 10, 11.

In Fig. 3 I have shown the timing condenser charging curves for a selected one of the condensers 34, 35 or 36. "Grid voltages" are plotted as ordinate against "Time" as abscissae. The grid voltage is that of grid 27. Curve A shows the characteristics secured when slider 31 is set at the upper end of resistor 8. The mark "Max. time" on the "Time" scale signifies the maximum interval or period of time secured before the thyratron is rendered non-conductive. The horizontal dash line B represents the critical grid potential of the thyratron. When curve A intersects curve B, the thyratron is rendered non-conductive. The remaining section of curve A is shown dashed to indicate the course of the curve if it were continued. Curve C represents the characteristic secured with slider 31 at the lower end of resistor 8. The legend "Min. time" denotes the fact that a minimum interval of time elapses with this setting of slider 31 before thyratron 20 is rendered non-conductive. Between curves A and C a family of curves may be chosen, depending on the setting of slider 31.

It will, then, be seen that in using the timer circuit of Fig. 1a, one must close the push switch 10, 11 momentarily. The timer will automat-

ically cycle itself. To recycle the timer the same procedure is repeated. Condensers 34, 35 and 36 may have values of 0.1, 0.5 and 4.0 microfarads respectively. These condensers should be of the type such that they possess a good power factor. For example, condensers having oil or high quality paper dielectric insulation are suitable. It is desirable to shunt coil 24 with resistor-condenser path 25, 26 to prevent chattering due to the alternating component flowing in the relay coil. Resistor 28 functions as an isolation resistor. Approximately a 10:1 ratio in time can be obtained by changing the amount of positive voltage applied to the timing condenser. This variation is obtained by the position of the potentiometer 8, 31, while greater changes in time may be obtained by selection of a larger or smaller timer condenser with range switch 33.

The timer circuit shown in Fig. 1a possesses several advantages. In the first place no power transformer is required. Standard 115 or 230 volts-60 cycle alternating current relays may be used in the thyratron plate circuit. It is necessary, however, that the resistance, inductance and capacity of the thyratron plate load circuit be so chosen that the peak and average currents are within tube ratings. Again, accuracy of re-set is maintained by the use of a relatively low value of potentiometer, and this low value of resistance permits the potentiometer 8, 31 to be wire-wound instead of carbon. Another advantage is that variations between tubes and variations throughout life have little effect upon accuracy, as the timer circuit always operates on the steep portion of the charging curve shown in Fig. 3. Still another advantage is the fact that the timer circuit is flexible, since large changes in time may be secured with the coarse range switch 33, while small or fine changes in time are obtained by the potentiometer 8, 31. It can be operated from several cycles of a 60 cycle wave to approximately 2 to 3 minutes. Still further advantages are that both sides of the load are made and broken by the relay; that the timer is of the "Fail-Safe" type; that momentary contact of the push switch 10 is all that is needed to make a timer go through its operational cycle; and, finally, that the condensers are discharged after every operational cycle, allowing for immediate recycling.

The timer circuit can be used in many mechanical and electric devices. For example, it may be used to time the exposure of photographic paper during printing or enlarging. In that case the lamp of the enlarging or printing apparatus is arranged to be selectively connected to the output terminals 2, 2' of the timer circuit shown in Fig. 1a. Again, the timing circuit can be used for welding.

In Fig. 2 I have schematically represented such a utilization. In this figure the push switch 10, 11 is schematically represented by the box 10', and the input terminals 1, 1' are shown connected to the rectangle labeled "Timer." It will be understood that the rectangle 50 includes all the apparatus shown in Fig. 1a between the input terminals 1, 1' and the output terminals 2, 2' as well as the push switch. As shown in Fig. 2, the welder electrodes 51 and 52 are connected to the opposite terminals of the secondary winding of output transformer 53. The output leads 2 and 2' are, of course, connected to the opposite ends of the primary winding of transformer 53. In this form of utilization the timer circuit furnishes a reliable system for timing the welding of materials placed between the electrodes 51 and

52. The push switch is usually connected in some manner such that the electrodes of the welder must be making good contact with the material to be welded before welding current is applied.

An additional use to which the timer circuit may be put is in connection with testing high current tube emission where a series of high current pulses are applied to a tube for two seconds, and the drop across the tube must be below a certain limit. It is necessary to use a timer for this testing since a large current passing through the cathode coating would increase the temperature due to the voltage drop through the coating. In this case, the timer circuit output leads are connected to a power supply source which in turn feeds a pulser which is responsive to a trigger circuit, and furnishes square wave pulses between the cathode and plate of a tube such as a thyratron. Many other uses are available with the timer circuit shown in Fig. 1a.

The following illustrative circuit constants are provided in order to enable those skilled in the art to construct the timer circuit, it being understood, however, that my invention is in no way limited to the specific circuit constants:

R ₁₅ , R ₇ -----	500 ohms.
R ₁₆ , R ₈ -----	1,500 ohms.
R ₂₉ , R ₂₈ -----	5 megohms.
R ₂₆ -----	5,000 ohms.
C ₁₂ , C ₁₇ -----	4 microfarads (mf.)
C ₃₄ -----	0.1 mf. of good power factor
C ₃₅ -----	.5 mf. of good power factor
C ₃₆ -----	4.0 mf. of good power factor
C ₂₆ -----	4 mf.

In Fig. 1b I have shown a modification of the timer system of Fig. 1a. The essential change involves the double contact-push switch which allows the timer to work its normal cycle even if the push switch is held in the "closed" position by the operator. The circuit is very similar to that shown in Fig. 1a, except that only two condensers 34 and 35 are used, condenser 36 being omitted. The timing condenser discharge line in Fig. 1b is traced as follows: point 37, lead 42, switch section 43', lead 42'', switch 41, 41', and lead 48. The switches 10, 11 and 42' are mechanically interconnected, as indicated by the parallel vertical dash lines. When the push switch is actuated to close switch 10, 11 the switch 42' is concurrently opened. Hence, the timing condenser discharge line through 42'' is opened, and the discharge of condenser 34 or 35 cannot take place until switch 42' is closed again. It will, therefore, be seen that the timer circuit will open after an interval upon thyratron 20 becoming non-conductive (as explained in connection with Fig. 1a). However, recycling will not be had until the push switch is released, and pressed again to close switch 10, 11. Release of the push switch permits the switch 42' to close thereby closing the discharge circuit, and clearing the timing condenser for a new cycle of timing.

The circuit arrangement of Fig. 1 may with relatively simple modifications be employed as a time delay relay or a time interval relay. These two circuit functions are respectively shown in Figs. 4 and 5. It will be noted during the course of the following description that the essential circuit elements of Figs. 4 and 5 respectively are quite similar to the circuit elements of Fig. 1a. In general, the time delay relay circuit of Fig. 4 is similar to the timer circuit of Fig. 1a, except for the fact that the grid 27 of thyratron tube 20 goes from a more negative potential to a more positive

potential. The timing comes from the fact that as the condenser 60 charges, the ratio of voltages across the resistances 61 and 62 will change.

The time interval timing circuit of Fig. 5 is similar to the timer circuit of Fig. 1a, except that the time intervals are controlled by the charging of the condenser 80 through the resistance 81, and the discharging of the condenser 80 is controlled through resistance 82. The relay in the anode circuit of the thyratron tube 20 is conducting, or made so that it is "off" when the thyratron is conducting.

A use for the time delay relay of Fig. 4 is in testing tubes where, after insertion of the tube in a socket, it is desirable to have a predetermined time before application of plate voltage in order that the heater may come up to temperature. The time interval relay of Fig. 5 may be used to test filaments in vacuum tubes, where the filament has a definite number of heatings and coolings throughout life. In this case the timer may be so arranged that the voltage is applied to the filament for 30 seconds and then held off for two minutes. Some of these tests go on as long as 100 hours.

Considering now the specific circuit connections shown in the time delay relay circuit of Fig. 4, it will be noted that the potentiometer slider 8, 31 is arranged in the anode circuit of diode D₁. In other words, the cathode 6 in this case is connected to the lead 5, while the anode 4 is connected to the low potential line 9 through the series resistors 7 and 8. The push switch 10 is adapted to connect the cathode 6 to the anode 14 of diode D₂, and the cathode of the latter diode is connected to lead 9 through resistors 15 and 16 which are in series. The timing condenser 60 has its upper terminal connected through resistor 62 to the junction point 19, while the lower terminal is connected through the lead 32 to the potentiometer slider 31.

The timing condenser 60 is shunted by a resistor 61, and the control grid 27 of thyratron tube 20 is connected through isolation resistor 28 to the upper terminal of condenser 60. The 60 cycle output leads 2 and 2' are connected respectively in the manner shown in Fig. 1a, except that the plate 23 of the thyratron tube 20 includes in its circuit the electromagnetic relay coil 24 which controls the opening and closing of switch 70. The output lead 2 is connected to the switch arm 71, while the fixed contact 72 of the switch 70 is connected to the upper end of relay coil or winding 24. The output lead 2' is connected to the cathode 21 of the thyratron tube. The relay winding 24 is shunted, as shown in Fig. 1a, by resistor 25 in series with condenser 26 to prevent chattering.

The time delay relay of Fig. 4 operates as follows: Switch 10 is closed. One-half of the double diode starts to charge condenser 17, at the same time, condenser 60 starts to charge. The charging current through resistor 62 is first negative at the grid end, and then progresses in the positive direction. When the critical grid value is reached the tube 20 goes into conduction, and will remain there until switch 10 is open. Switch 10 is usually a knife or toggle switch, and would seldom be a "push" switch. Resistor 61 is the discharge resistor for condenser 60.

The specific circuit connections of the time interval relay circuit shown in Fig. 5, also, bear a substantial resemblance to the circuit of Fig. 1a. As stated previously, the time interval relay circuit differs in that the time intervals are con-

trolled by the charging of condenser 80 through the resistance 81, and the discharging of the condenser through resistance 82 of small value. However, it will be noted that there is no push switch employed in this circuit arrangement. The schematically represented source of energizing voltage 90 has one terminal thereof connected through the lead 5 to the upper terminal of the relay winding 24, while the opposite terminal of source 90 is connected to the low potential line 22. The double diode tube 3 has the anode of diode D₁ connected in common with the cathode of diode D₂ through lead 91 to the contact point 39 of the double pole-double throw switch. The contact 41 is connected to an output lead 2, and the lead 2' is connected to contact 39. The contact 38 is free.

The contact 40 is connected through resistor 82 and lead 92 to the junction of resistors 7 and 8. The junction of resistors 15 and 16 is connected through resistor 81 and isolation resistor 28 to the control grid 27 of the thyratron tube 20. The junction of resistors 28 and 81 is connected through the timing condenser 80 to lead 29, thereby connecting the lower terminal of condenser 80 to the junction of resistors 7 and 8 and to the lower end of resistor 82. The switch arms 45 and 45' are conductively connected by lead 93 to the junction of resistors 28 and 81, while the switch arms 47 and 47' are connected through lead 94 to the line 5. In the time interval relay circuit of Fig. 5, it is an essential feature that "on" period can be made when the thyratron tube 20 is conducting, or made so that it is "off" when the thyratron is conducting. It will, also, be noted that there is an intermediate output lead 2" from the low potential side of the system.

The operation of the time interval relay is identical to the timer shown in Fig. 1a, with the exception that there is no initiating, or push, switch. Further, resistor 82 determines the discharge rate of condenser 80. The "off" time is the time it takes condenser 80 to discharge. The diodes D₁ and D₂ are connected through one contact of the relay. It is pointed out that condensers 12 and 17 discharge very quickly to permit recycling.

While I have indicated and described several systems for carrying my invention into effect, it will be apparent to one skilled in the art that my invention is by no means limited to the particular circuit organizations shown and described, but that many modifications may be made without departing from the scope of my invention.

What I claim is:

1. In an apparatus for controlling the conduction of pulsating current between a pair of alternating current input terminals, the combination of first and second rectifier circuits connecting said terminals, each said circuit including a serially connected rectifier and capacitor, said rectifiers being connected in said circuits in opposite polarity to conduct current between said terminals in opposite directions to develop across said capacitors voltages of opposite polarity with respect to one of said input terminals, an electron discharge device having an anode, a cathode and a control grid, means connecting said anode and said cathode to opposite ones of said input terminals to provide a path for pulsating current flow between said terminals, a third circuit connected between a point of positive potential in said first circuit and a point of negative potential in said second

circuit, said third circuit including a serially connected resistor and a third capacitor, and means connecting said control grid to the junction point between said resistor and said third capacitor.

2. An apparatus as defined in claim 1 including a resistor connected in parallel with said capacitor in said first circuit, and a slider contact on said resistor to establish said positive potential point in said first circuit.

3. An apparatus as defined in claim 1 including a resistor connected in parallel with said capacitor in said second circuit, and a slider contact on said resistor to establish said negative potential point in said second circuit.

4. An apparatus as defined in claim 1 including a switch common to said first rectifier circuit and to said path.

5. In an apparatus for controlling the conduction of pulsating current between a pair of 20 alternating current input terminals, the combination of first and second rectifier circuits connecting said terminals, each said circuit including a serially connected rectifier and capacitor, said rectifiers being connected in said circuits to conduct current between said terminals in opposite directions to develop across said capacitors voltages of opposite polarity with respect to one of said input terminals, an electron discharge device having an anode, a cathode and a control grid, means connecting said anode and said cathode to opposite ones of said 30 input terminals to provide a path for pulsat-

ing current flow between said terminals, a third circuit connected between a point of positive potential in said first circuit and a point of negative potential in said second circuit, said third circuit including a serially connected resistor and a third capacitor, means connecting said control grid to the junction point between said resistor and said third capacitor, and means responsive to pulsating current flow through said device for discharging said last named capacitor.

6. Apparatus as defined in claim 5 wherein said last named means comprises a relay having an operating winding connected serially with said tube in said path, said relay having a pair 15 of contacts adapted to close in response to energization of said relay, said contacts being connected to opposite plates of said third capacitor.
